[57] CLAIM

The ornamental design for a game board carrier, as shown and described.

DESCRIPTION

FIG. 1 is a reduced front elevational view of a game board carrier in an open posture embodying my design;

FIG. 2 is a folded front elevational view of the carrier seen in FIG. 1;

FIG. 3 is a right side elevational view of the carrier as seen in FIG. 2;

FIG. 4 is a rear, top, right side perspective view thereof;

FIG. 5 is a top plan view thereof;

FIG. 6 is a bottom plan view thereof; and,

FIG. 7 is a left side elevational view thereof.
